UNITED STATES PATENT OFFICE

FREDERICK W. ROETTGES, OF NEW YORK, N. Y., ASSIGNOR TO WROUGHT IRON & ART GLASS FIXTURE CO. INC., OF NEW YORK, N. Y.

DESIGN FOR A LIGHTING-FIXTURE ORNAMENT OR ARTICLE OF SIMILAR NATURE

Application filed July 16, 1930. Serial No. 36,362. Term of patent 3½ years.

To all whom it may concern:

Be it known that I, FREDERICK W. ROETTGES, a citizen of Germany, residing in New York, in the county of Kings and State of New York, have invented a new, original, and ornamental Design for a Lighting-Fixture Ornament or Article of Similar Nature, of which the following is a specification, reference being had to the accompanying drawing, forming a part thereof.

The figure is a perspective view of a lighting fixture ornament showing my new design.

I claim:

The ornamental design for a lighting-fixture ornament, or article of similar nature, as shown.

In testimony whereof I affix my signature.

FREDERICK W. ROETTGES.
